AUTOMOBILE GASOLINE DOOR GUARD

Perry E. Allen, 4644 Round Hill Road,
Birmingham, Mich. 48010

Filed Mar. 20, 1968, Ser. No. 11,052

Term of patent 14 years

U.S. Cl. D14—6
Int. Cl. D12—14

FIG. 1 is a front elevational view of an automobile gasoline door guard embodying my new design.

FIG. 2 is a left end view thereof.

FIG. 3 is a top view thereof.

I claim:

The ornamental design for an automobile gasoline door guard, as shown.
